(57) **CLAIM**

The ornamental design for mirror for a work machine, as shown and described.

DESCRIPTION

FIG. 1 is rear perspective view of a first embodiment of a mirror for a work machine;

FIG. 2 is a front perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The second embodiment of the mirror for a work machine is a mirror image of the first embodiment disclosed in FIGS. 1-8.

1 Claim, 4 Drawing Sheets(56)
